STRAND HANDLING APPARATUS

John N. Selvig, Westfield, N. J., assignor to Western Electric Company, Incorporated, New York, N. Y., a corporation of New York

Application July 9, 1937, Serial No. 152,693

12 Claims. (Cl. 242—147)

This invention relates to strand handling apparatus, and more particularly to means for tensioning a strand while being advanced longitudinally.

There is an almost countless variety of apparatus in which it is necessary or desirable to draw a strand from some supply thereof which allows the strand to be drawn off substantially without resistance, and then to impose upon the strand a definite, predetermined and adjustably invariable tension, ordinarily by passing the strand through some device or apparatus which presents an adjustably variable degree of resistance to the passage of the strand. In the past, many such devices have been made to depend upon friction in one form or another, either directly on the strand itself or on a member, such as a sheave for example, driven by the strand. Devices dependent upon friction, while in many cases satisfactory for the immediate purpose in view, are notoriously difficult to keep in adjustment and properly regulated, perhaps because of wear due to the friction employed itself, perhaps due to changes in character of one or another friction member employed, e. g., changes deriving from varying absorption in or adsorption on the friction member of moisture under varying meteorological conditions, or perhaps for other reasons.

An object of the present invention is to produce an apparatus or device for imposing tension upon a strand being drawn therethrough in which the resistance offered to the passage of the strand is substantially independent of any frictional effect whatsoever, whether exerted upon the strand itself or by means of other elements related to the strand.

With the above and other objects in view, one embodiment of the invention may comprise a system of sheaves, rollers or the like, over which the strand passes in a tortuous path, in particular being bent or flexed over an arc of predetermined but adjustably or interchangeably variable length or radius or both, the effective resistance of the strand to passing through the apparatus or device being due primarily to the said bending or flexing, all other causes of resistance and particularly frictional effects being obviated so far as possible.

Other objects and features of the invention will appear from the following detailed description of an embodiment thereof, taken in connection with the appended drawing in which the same reference numerals are applied to identical parts in the several figures and in which

Fig. 1 is a perspective view of simple form of embodiment of the invention in a device for tensioning a single strand;

Fig. 2 is a similar view of a slightly modified form of the device of Fig. 1;

Fig. 3 is a similar view of a second modified form;

Fig. 4 is a perspective view of a third modified form adapted to impose equal tension and equal longitudinal speed upon a plurality of strands; 5

Fig. 5 is a view in side elevation of a fourth modified form to handle one strand, and

Fig. 6 is a perspective view of a fifth modification.

In the preferred embodiment shown in Fig. 1, 10 any convenient member 10 is employed as the base or support of the device. In the present instance, the member 10 may be thought of as an angle iron bar which is part of the framework of some apparatus for treating or handling a strand 11 in some manner whose exact nature is not relevant here. There is presumed to be some means, not shown, for propelling or drawing the strand 11 off to the right; and the strand is drawn through the disclosed device 20 from some supply or source below, also not disclosed, which might well be merely a loose coil of the strand lying on the floor or other support, or might be a cop or spool or any other source from which the strand 11 may be drawn substantially without resistance. 25

The strand comes up from the source through a substantially resistanceless guide such as the pigtail 12 mounted at 13 on the base 10, passes over the roller 14, under the roller 15, over the roller 16 and so out to the propelling means. The rollers 14 and 16 are preferably identically alike, each being mounted by means of an anti-friction bearing 17 or 19 on a stub shaft 20 or 22 carried by the base 10. The roller 15 is mounted by means of an anti-friction bearing 18 on a shaft 21 carried by a spring arm 24 secured at 25 to the base member 10. The spring arm 24 is a convenient means to allow the roller 15 to be drawn away slightly from the rollers 14 and 16, as indicated in dotted lines, when a strand is to be threaded into place in the device. 30

The rollers 14, 15 and 16 have the same axial length, and each is formed with a peripheral groove or channel between peripheral flanges at 45 the ends. These rollers may be of any convenient axial length, provided only that the space between the two flanges of each roller is enough wider than the diameter of the strand 11 so that the latter rides clearly on the bottom of 50 14, 15 and 16 to rotate in the respective directions of the groove or channel and does not have lateral and frictional contact with the flanges.

When the device is threaded with the strand 55 11 as shown in Fig. 1, the roller 15 is held up by the spring arm 24 or the tension of the strand 11 or both to have its flanges in direct peripheral contact with the flanges of the rollers 14 and 16. The rollers 14 and 16 are pro- 60

portioned and mounted to be out of contact with each other.

As the strand 11 is drawn along in the direction of the straight arrows, it causes the rollers 14 and 16 to roll on the flanges of the rollers 14 and 16 without slip. The diameters of the three sets of flanges and of the bottoms of the three grooves or channels, 10 on which the strand lies, are so proportioned and related that, when the roller 15 rolls without slip on the rollers 14 and 16 as described, the peripheral speeds of the grooved or channelled parts of the three rollers will be alike, 15 so that the strand can run simultaneously over all three without having to slip on any.

When the device is constructed and arranged, and is operating in the manner described, there will be no frictional resistance to the advance 20 of the strand of any magnitude which is not negligible in comparison to the resistance occasioned by the bending of the wire in its passage over the three rollers. In particular, if the roller 15 be of considerably less diameter where 25 the strand passes around it, the chief portion of the resistance developed by the entire device will be due to the bending of the strand around the roller 15.

Also, if the anti-friction bearing 18 of the 30 roller 15 be made easily removable from the shaft 21, then the roller 15 and its bearing may be conveniently and easily interchanged for another roller of greater or smaller channel diameter and the tension imposed by the device upon a given strand may be quickly and easily changed as desired to a smaller or greater tension.

Fig. 2 shows a slightly modified form of the device of Fig. 1, in which the roller 15 rests on and is supported by the rollers 14 and 16. This arrangement obviates the necessity of providing equivalents for the bearing 18, shaft 21 and arm 26, but has the possible disadvantage of leaving the roller 15 loose to be dropped and perhaps damaged when threading the apparatus or interchanging rollers 15.

Fig. 3 shows a second modification of the device of Fig. 1, in which the strand is drawn in the other direction and the roller 14 and its bearing and shaft are omitted. While this form operates satisfactorily in many instances, it does not always have the extreme steadiness of action of the two forms described above.

Fig. 4 discloses an application of the device of Fig. 2 in which several such devices are associated together to control a like number of parallel running strands. In this case each strand 11, 111 or 211 has its own independent rollers 14 and 16, 114 and 116, or 214 and 216 respectively, but the several principal rollers 15 are replaced by a single unitary roller, barrel or shaft 150. To enable this arrangement, the rollers 14, 114 and 214 must be coaxially located and likewise the rollers 16, 116 and 216. Where the member 150 is a plain cylinder as shown, the action will be triflingly imperfect as the peripheral speed of the cylinder 150 and of the channel bottoms in the other rollers will differ a little, so that the strands will slip a little on the cylinder. However, this may be overcome by cutting peripheral channels 65 of suitable depth and width in the cylinder at the several places where the strands run over it. When thus arranged, the device not only imposes equal tension upon all the strands but also forces them to run at equal speeds.

In Fig. 5 is disclosed a modification of the de-

vice in which not only may the principal roller 15 be interchanged for others of other diameter as indicated by dotted circles, but also the length of the arc of contact on the roller 15 may be altered, e. g. by turning the screw 26 to bring the rollers 14 and 16 closer together or further apart.

While in most cases the very simple arrangements shown will operate entirely satisfactorily as described; it may be desirable, especially if the strand 11 be extremely fine, to drive the rollers 14, 15 and 16 by independent means instead of by the strand itself. In such a case, as disclosed in Fig. 6, the flanges of the three rollers 14, 15 and 16 might be provided with mutually intermeshing 15 gear teeth, and one of the rollers, preferably perhaps roller 16, be driven by a suitably driven gear 27 applied thereto at a convenient point on its periphery. In such case the rollers would be driven so that their common peripheral speed at 20 the bottoms of their channels would be that desired for the longitudinal speed of the strand.

The embodiment of the invention and its modifications, herein disclosed are merely illustrative and may be modified and departed from in many 25 ways without departing from the scope and spirit of the invention as pointed out in and limited only by the appended claims.

What is claimed is:

1. A device for imposing tension on a strand 30 being drawn therethrough, which device consists solely so far as tensioning effect is concerned of a plurality of rollers over which the strand passes in a tortuous path, the rollers being driven to have peripheral speeds equal to each other and 35 equal to the longitudinal speed of the strand, and the parts being so proportioned and arranged that substantially all of the resistance to the passage of the strand through the device is due to the bending only of the strand in passing over the 40 rollers.

2. A device for imposing tension on a strand being drawn therethrough, which device consists solely so far as tensioning effect is concerned of a plurality of rollers over which the strand passes 45 in a tortuous path, the rollers being driven by the strand to have peripheral speeds equal to each other and equal to the longitudinal speed of the strand, and the parts being so proportioned and arranged that substantially all of the resistance 50 to the passage of the strand through the device is due to the bending only of the strand in passing over the 55 rollers.

3. A device for imposing tension on a strand being drawn therethrough, which device consists solely so far as tensioning effect is concerned of a plurality of rollers over which the strand passes 60 in a tortuous path, the rollers being driven independently of the strand to have peripheral speeds equal to each other and equal to the longitudinal 65 speed of the strand, and the parts being so proportioned and arranged that substantially all of the resistance to the passage of the strand through the device is due to the bending only of the strand in passing over the 70 rollers.

4. A device for imposing adjustable tension on a strand being drawn therethrough, which device consists solely so far as tensioning effect is concerned of a plurality of rollers over which the strand passes in a tortuous path, the rollers being 75 driven to have peripheral speeds equal to each other and equal to the longitudinal speed of the strand, the parts being so proportioned and arranged that substantially all of the resistance to the passage of the strand through the device is 75

due to the bending only of the strand in passing over the rollers, and means to mount one of the rollers to be removable and thereby interchangeable to vary the tension imposed on the strand by varying the diameter of the interchangeable roller.

5. A device for imposing tension on a strand being drawn therethrough, which device consists solely so far as tensioning effect is concerned of a plurality of rollers over which the strand passes in a tortuous path, each roller having a peripheral channel to receive the strand between peripheral flanges and which channel is wider than the strand to avoid friction between the strand and the flanges, the rollers being driven to have peripheral speeds in their channel bottoms equal to each other and equal to the longitudinal speed of the strand, and the parts being so proportioned and arranged that substantially all of the resistance to the passage of the strand through the device is due to the bending only of the strand in passing over the rollers.

6. A device for imposing adjustable tension on a strand being drawn therethrough, which device consists solely so far as tensioning effect is concerned of a plurality of rollers over which the strand passes in a tortuous path, each roller having a peripheral channel to receive the strand between peripheral flanges and which channel is wider than the strand to avoid friction between the strand and the flanges, the rollers being driven to have peripheral speeds in their channel bottoms equal to each other and equal to the longitudinal speed of the strand, the parts being so proportioned and arranged that substantially all of the resistance to the passage of the strand through the device is due to the bending only of the strand in passing over the rollers, and means to mount one of the rollers to be removable and thereby interchangeable to vary the tension imposed on the strand by varying the diameter of the interchangeable roller.

7. A device for imposing tension on a strand being drawn therethrough, which device comprises a plurality of rollers over which the strand passes in a tortuous path, each roller having a peripheral channel to receive the strand between peripheral flanges and which channel is wider than the strand to avoid friction between the strand and the flanges, the rollers being arranged in a sequence with the flange peripheries of each in contact with the rolling without sliding friction on the flange peripheries of the next, the rollers having their channel diameters proportioned and being driven to have peripheral speeds in their channel bottoms equal to each other and equal to the longitudinal speed of the strand, and the parts being so proportioned and arranged that substantially all of the resistance to the passage of the strand through the device is due to the bending only of the strand in passing over the rollers.

8. A device for imposing tension on a strand being drawn therethrough, which device comprises a plurality of rollers over which the strand passes in a tortuous path, each roller having a peripheral channel to receive the strand between peripheral flanges and which channel is wider than the strand to avoid friction between the strand and the flanges, the rollers being arranged in a sequence with the flange peripheries of each in contact with and rolling without sliding friction on the flange peripheries of the next, the rollers having their channel diameters proportioned and being driven by the strand passing

thereover to have peripheral speeds in their channel bottoms equal to each other and equal to the longitudinal speed of the strand, and the parts being so proportioned and arranged that substantially all of the resistance to the passage of the strand through the device is due to the bending only of the strand in passing over the rollers.

9. A device for imposing tension on a strand being drawn therethrough, which device comprises a plurality of rollers over which the strand passes in a tortuous path, each roller having a peripheral channel to receive the strand between peripheral flanges and which channel is wider than the strand to avoid friction between the strand and the flanges, the rollers being arranged in a sequence with the flange peripheries of each in contact with and rolling without sliding friction on the flange peripheries of the next, the rollers having their channel diameters proportioned and being driven by the strand passing thereover to have peripheral speeds in their channel bottoms equal to each other and equal to the longitudinal speed of the strand, the parts being so proportioned and arranged that substantially all of the resistance to the passage of the strand through the device is due to the bending only of the strand in passing over the rollers, and one of the rollers being interchangeable to vary the tension imposed on the strand by varying the diameter of the interchangeable roller.

10. A device for imposing tension on a strand being drawn therethrough, which device comprises a plurality of rollers over which the strand passes in a tortuous path, each roller having a peripheral channel to receive the strand between toothed peripheral flanges and which channel is wider than the strand to avoid friction between the strand and the flanges, the rollers being arranged in a sequence with the toothed flange peripheries of each in mesh with those of the next, the rollers having their channel diameters proportioned and being driven independently of the strand to have peripheral speeds in their channel bottoms equal to each other and equal to the longitudinal speed of the strand, and the parts being so proportioned and arranged that substantially all of the resistance to the passage of the strand through the device is due to the bending only of the strand in passing over the rollers.

11. A device for imposing tension on a strand being drawn therethrough, a plurality of freely and substantially frictionlessly rotatable rollers each having a peripheral channel to receive the strand between peripheral flanges and which channel is wider than the strand, the rollers being arranged in a sequence relatively to each other so that the peripheries of the flanges of each roller are in contact with and roll on the peripheries of the flanges of the next roller, and the flange diameter and the channel bottom diameter of each roller being in such ratio that when any two rollers have equal tangential speeds at the peripheries of their flanges, they will also have equal tangential speeds at their channel bottoms.

12. In a device for imposing tension on a strand being drawn therethrough, a pair of rollers over which the strand may pass, each roller having a flange portion of one diameter and a reduced portion of smaller diameter, the ratio of the two diameters of each roller to each other being equal to the same ratio of the two diameters of the other roller.
